1

This invention relates to a new class of quaternary amines and, more particularly, to quaternary amines containing fluorine and processes for their preparation.

I have advanced the quaternary amine art by providing a novel group of such amines having one or more fluorine atoms attached to a carbon atom of the cationic radical.

The cationic radical may have the fluorine atom or atoms attached to a carbon atom in any portion of its structure, according to my invention. Thus, in quaternary amines having a cationic radical having alkyl groups of varying chain lengths, as two lower alkyl (C₁ to C₈) groups, and a higher alkyl (C₉ to C₁₈) group, along with a ring-containing group, attached to the pentavalent nitrogen atom, the fluorine may be present as a substituent on any one or more of the carbon atoms of these groups.

Many of the compounds of my invention are crystalline substances, which may be dissolved in water. They are substantially odorless and practically non-toxic to mammals.

A comparison of the bactericidal or germicidal properties of the compounds of this invention with those of a commercial prior art quaternary compound, dodecyldimethylbenzyl ammonium chloride, which has a phenol coefficient at 20 degrees centigrade against *E. typhi* of about 250, and against *S. aureus* of about 280, shows that my compounds are considerably more potent as germicides; dodecyldimethyl - 3 - (trifluoromethyl)benzylammonium chloride, for example, being about three times more effective. The other compounds of my invention possess like disinfecting properties.

An acute toxicity determination indicates that certain of the compounds of my invention are substantially less toxic than the corresponding quaternary amines not containing fluorine in the cationic portion of the molecule. For example, the product of Example VII; namely, dodecyldimethyl - 3 - (trifluoromethyl)benzylammonium chloride, has been found by acute toxicity determinations to be about ten times less toxic than dodecyldimethylbenzylammonium chloride.

Skin irritation tests on humans show that certain of the compounds of my invention are also non-sensitizers, dodecyldimethyl - 3 - (trifluoromethyl)benzylammonium chloride being less irri-

2

tant than the quaternary amines commercially available for germicidal use.

The anion attached to the pentavalent nitrogen atom of my compounds is preferably selected from the group of anions of organic and inorganic acids, such as the halides (including fluorine), nitrates, cyanides, hydroxides, sulfates, alkyl sulfates, phosphates, orthophosphates, or the salts with organic acids, for instance, the formates, acetates, lactates, tartrates, citrates, benzene or toluene sulfonates, benzoates, salicylates, hydrocinnamates, et cetera.

More particularly, this invention includes compounds of the above general type wherein two lower alkyl groups are attached to the pentavalent nitrogen atom or, the said nitrogen atom is part of a heterocyclic radical, i. e., an N-heterocycle; one higher alkyl group of about 9 to 18 carbon atoms, including odd number carbon branched-chain groups resulting from the Oxo process, is attached to said nitrogen atom, and, an alkyl-aralkyl or alkyl-cycloalkylalkyl group containing at least one fluorine atom and preferably as a trifluoromethyl group, is attached to said nitrogen atom. Still further this invention preferably includes those quaternary amines which contain attached to the nitrogen atom, an aralkyl group having a trifluoromethyl group in the meta position.

The preferred quaternary amines of this invention having a ring-containing group attached to the pentavalent nitrogen atom with at least one fluorine atom attached to said group can be prepared by reacting stoichiometric amounts of a salt such as the chloride, sulfate, et cetera, of the ring-containing group containing fluorine with the selected tertiary amine. The reaction is conducted at room temperature for a period of about six hours and then the reaction mixture is heated for approximately ten hours at a temperature of about 80 to 100 degrees centigrade to complete the reaction. Alternatively, the two reactants may simply be placed in a reaction vessel, mixed, and heated to the reaction temperature immediately thereafter. The reaction may be effected in anhydrous or aqueous media. The crude reaction products obtained may be purified by recrystallization from various solvents, such as ethyl acetate, pentane, mixtures thereof, acetone, et cetera, or by removing impurities by vacuum or steam

distillation. Other quaternary amines of my invention may be prepared by reacting a substituted tertiary amine containing fluorine in an alkyl group, with an organic salt.

The following examples are illustrative of the invention:

Example I.—Decyldimethyl-4-(trifluoromethyl)-benzylammonium chloride

Two and ninety-two hundredths parts (0.015 mole) of 4-(trifluoromethyl)benzyl chloride was reacted with 2.6 parts (0.014 mole) of decyldimethylamine by heating a mixture of the reactants at a temperature of about 80 degrees centigrade for a period of about ten hours. The product so obtained was purified by two crystallizations from ethyl acetate, followed by removal of the solvent in a vacuum desiccator over phosphorus pentoxide. Three and one-half parts (0.0092 mole) of decyldimethyl-4-(trifluoromethyl)benzylammonium chloride was thus recovered, amounting to 66 per cent of the theoretical. The product analyzed as follows:

$C_{20}H_{33}ClF_3N$; calcd. 9.33% Cl; found 9.28% Cl.

In a manner after Example I, the following compounds were prepared, in the yields indicated, in accordance with the reactions as illustrated below.

Example II.—Dodecyldimethyl-4-(trifluoromethyl)benzylammonium chloride

It analyzed as follows: $C_{22}H_{37}ClF_3N$; 86% yield; calcd. 8.71% Cl; found 8.69% Cl.

Example III.—Tetradecyldimethyl-4-(trifluoromethyl)benzylammonium chloride

It analyzed as follows: $C_{24}H_{41}ClF_3N$; 80% yield; calcd. 8.14% Cl; found 8.05% Cl.

Example IV.—Hexadecyldimethyl-4-(trifluoromethyl)benzylammonium chloride

It analyzed as follows: $C_{26}H_{45}ClF_3N$; 85% yield; calcd. 7.65% Cl; found 7.70% Cl.

Example V.—Octadecyldimethyl-4-(trifluoromethyl)benzylammonium chloride

10

It analyzed as follows: $C_{28}H_{49}ClF_3N$; 85% yield; calcd. 7.20% Cl; found 7.13% Cl.

Example VI.—Decyldimethyl-3-(trifluoromethyl)benzylammonium chloride

20

It analyzed as follows: $C_{20}H_{33}ClF_3N$; 63% yield; calcd. 9.30% Cl; found 9.32% Cl.

Example VII.—Dodecyldimethyl-3-(trifluoromethyl)benzylammonium chloride

25

It analyzed as follows: $C_{22}H_{37}ClF_3N$; 88% yield; calcd. 8.70% Cl; found 8.70% Cl.

Example VIII.—Tetradecyldimethyl-3-(trifluoromethyl)benzylammonium chloride

30

It analyzed as follows: $C_{24}H_{41}ClF_3N$; 72% yield; calcd. 8.14% Cl; found 8.24% Cl.

Example IX.—Hexadecyldimethyl-3-(trifluoromethyl)benzylammonium chloride

35

It analyzed as follows: $C_{26}H_{45}ClF_3N$; 87% yield; calcd. 7.65% Cl; found 7.62% Cl.

Example X.—Octadecyldimethyl-3-(trifluoromethyl)benzylammonium chloride

40

It analyzed as follows: $C_{28}H_{49}ClF_3N$; 88% yield; calcd. 7.20% Cl; found 7.22% Cl.

Example XI.—Decyldimethyl-3,5-bis(trifluoromethyl)benzylammonium chloride

45

It analyzed as follows: $C_{28}H_{49}ClF_3N$; 85% yield; calcd. 7.20% Cl; found 7.13% Cl.

5

It analyzed as follows: $C_{21}H_{32}ClF_6N$; 66% yield; calcd. 7.9% Cl; found 7.84% Cl.

Example XII.—Dodecyldimethyl-3,5-bis(trifluoromethyl)benzylammonium chloride

It analyzed as follows: $C_{23}H_{36}ClF_6N$; 78% yield; calcd. 7.45% Cl; found 7.40% Cl.

Example XIII.—Tetradecyldimethyl-3,5-bis(trifluoromethyl)benzylammonium chloride

It analyzed as follows: $C_{25}H_{40}ClF_6N$; 68% yield; calcd. 7.04% Cl; found 7.05% Cl.

Example XIV.—Hexadecyldimethyl-3,5-bis(trifluoromethyl)benzylammonium chloride

It analyzed as follows: $C_{27}H_{44}ClF_6N$; 84% yield; calcd. 6.67% Cl; found 6.65% Cl.

Example XV.—Octadecyldimethyl-3,5-bis(trifluoromethyl)benzylammonium chloride

It analyzed as follows: $C_{29}H_{48}ClF_6N$; 87% yield; calcd. 6.33% Cl; found 6.26% Cl.

Example XVI.—Dodecyldimethyl (2-nitro-4-trifluoromethyl)phenylammonium chloride

Example XVII.—Dodecyldimethylchloro-bis(trifluoromethyl)phenylammonium chloride

6

Example XVIII.—Dodecyldimethyl-4-fluoro-benzylammonium chloride

Example XIX.—Dodecyltrifluoromethylbenzylmorpholinium chloride

Example XX.—Dodecyl-bis-(B-trifluoroethyl)-benzylammonium chloride

Example XXI.—Difluorocetyl-dimethyl-benzylammonium chloride

Quaternary ammonium compounds having a fluorine atom on the nitrogen atom may be prepared by converting the corresponding quaternary ammonium chloride to the fluoride by treatment with hydrated silver oxide, to form the hydroxide, followed by neutralization of the hydroxide with aqueous hydrogen fluoride. The following examples are illustrative:

Example XXII.—Dodecyldimethyl-3-(trifluoromethyl)benzylammonium fluoride

Twenty and three-tenth parts (0.05 mole) of dodecyldimethyl - 3 - (trifluoromethyl)benzylammonium chloride was reacted with hydrated silver oxide to yield dodecyldimethyl-3-(trifluoromethyl)benzylammonium hydroxide, which was then reacted with aqueous hydrogen fluoride to give the corresponding fluoride. After purification 6.2 parts of product was recovered. It analyzed as follows: $C_{22}H_{37}F4N$; 3.58 N; found: 3.68% N.

Example XXIII.—Hexadecyldimethyl-3-(trifluoromethyl)benzylammonium fluoride

Twenty-three and one-tenth parts (0.05 mole) of the chloride was reacted in the manner of Example XXII. After purification 5.5 parts of product was recovered, and it was found to contain 3.13% N.

The surface active properties of the compounds of this invention in Table I were tested by using the method of Draves (American Dyestuff Reporter, vol. 28, page 425, 1939). The Draves test is the time in seconds for a standard 5 gram cotton test skein to sink when attached by a $\frac{3}{4}$ inch string to a 3.0 gram copper hook, when placed in a cylindrical vessel of 500 ml. capacity with the concentration of quaternary of 1.0 gram per liter. Thus, the shorter the test time, the better the wetting power of the compound being tested.

10

5

15

20

25

By comparing the Draves test time of the above "dodecyl" compounds of this invention with that of a commercial sample of the prior art dodecyl-dimethylbenzyl ammonium chloride, having a test time of 374 seconds, it may be seen that the corresponding compounds of my invention are at least 16 times more effective, and in the case of dodecyl-dimethyl-3-(trifluoromethyl) benzyl ammonium fluoride, this compound is 93 times more effective as a wetting agent.

Also comparison of the Draves test time of the above "hexadecyl" compounds of this invention with that of a sample of the prior art hexadecyl dimethyl benzyl ammonium chloride having a test time of 620 seconds, shows my compounds to be at least about 8 times more effective and as much as about 25 times more effective than the corresponding prior art compound.

The bactericidal or germicidal properties of the compounds of this invention listed in Table II were tested according to the method of the U. S. Food and Drug Administration (Circular 198, December 1931), using *E. typhi* and *S. aureus*. Exposures were at 20° C.; the results are reported in phenol coefficients and effective dilutions.

Many of the compounds of my invention, specified, are crystalline substances, which may be dissolved in water. They are substantially odorless and practically non-toxic to mammals. Certain of the compounds of my invention containing varying amounts of fluorine in the molecule, which possess enhanced germicidal activity and very low toxicity, are contemplated as being useful in oral therapy as disinfectants, and particularly for prevention of dental caries, by virtue of their fluorine content.

By means of this invention a whole new class of quaternary ammonium compounds is made available. Although I have described my invention by illustrating certain specific embodiments thereof, various modifications may be made without departing from the spirit and scope thereof, and consequently, I do not intend that it shall be limited except as defined in the appended claims.

I claim:

1. A member of the group consisting of a di-lower alkyl, higher alkyl, quaternary ammonium salt having a monocyclic aromatic hydrocarbon ring-containing group attached to the pentavalent nitrogen atom and a N-higher alkyl, morpholinium quaternary ammonium salt having a monocyclic aromatic hydrocarbon ring-containing group attached to the pentavalent nitrogen atom, wherein the aromatic ring contains a

fluoromethyl radical, said higher alkyl having from 9 to 18 carbon atoms.

2. A compound according to claim 1 wherein the fluoromethyl radical is a trifluoromethyl radical.

3. A compound according to claim 1 wherein the ring-containing group attached to the pentavalent nitrogen atom is a benzyl group containing at least one trifluoromethyl radical.

4. A compound according to claim 1 wherein the ring-containing group attached to the pentavalent nitrogen atom is a phenyl group containing at least one trifluoromethyl radical.

5. A compound according to claim 2 wherein a trifluoromethyl radical is attached in the meta position.

6. Dodecyl-dimethyl-3 - (trifluoromethyl) benzyl-ammonium chloride.

7. Dodecyldimethyl-4 - (trifluoromethyl) benzyl-ammonium chloride.

8. Dodecyldimethyl - 3,5 - bis(trifluoromethyl) benzylammonium chloride.

9. Dodecyl-3-(trifluoromethyl) benzyl-morpholinium chloride.
